UNITED STATES PATENT OFFICE

2,036,048

DUAL WIPER OR APPLICATOR

Anthony P. Hinsky, Brooklyn, N. Y., assignor to
 Pyro Products Corporation, Brooklyn, N. Y., a
 corporation of New York

Application October 26, 1933, Serial No. 695,246

13 Claims. (Cl. 91—53)

This invention relates to the production of wires or electric conductors, cables or other strand-like bodies treated with various types of coating materials; and the object of the invention is to provide a wiper or applicator by means of which such coating materials may be evenly deposited upon the wire or other strand-like body to provide a substantially even thickness of the coating material on the strand and for the purpose of removing the surplus of a saturant compound or other coating from the outer surface, casing or jacket of a strand; a further object being to provide a wiper or applicator having a dual nozzle or passage into and through which the strand is passed, one passage being formed by a die employed for removing the greater part of the surplus of material applied to the strand and the other in the form of a flexible member having a passage therein controlling the finished size, contour and characteristics of the material applied to the strand; a further object being to provide means cooperating with said flexible member to vary the size of the port or passage therethrough without distortion to the contour of said passage and without changing its alignment with respect to the passage in said die; a further object being to provide a dual wiper unit of the class described with means for adjustably mounting the unit in connection with a support to change its position vertically and angularly with respect to the support to maintain an alignment of the dual passages of the wiper with respect to guide rollers or sheaves disposed outwardly of and at opposite ends of the unit so as to maintain the passages of the unit properly centered with respect to a strand passing over said spaced sheaves; and with these and other objects in view, the invention consists in an apparatus of the class specified, as well as a method of treating or coating strands with said apparatus as is more fully hereinafter described and claimed.

The invention is fully disclosed in the following specification, of which the accompanying drawings forms a part, in which the separate parts of my improvement are designated by suitable reference characters in each of the view, and in which:

Fig. 1 is a diagrammatic view indicating the method of applying a saturant or compound to a strand by the use of my improved device of apparatus.

Fig. 2 is a sectional view through a dual wiper which I employ showing the parts substantially in the position indicated in Fig. 1.

Fig. 3 is a partial section on the line 3—3 of Fig. 2.

Fig. 4 is a partial section on the line 4—4 of Fig. 2.

Fig. 5 is a view looking in the direction of the arrow 5 of Fig. 2 with parts indicated in open position in dotted lines.

Fig. 6 is a detail view of a modified form of die which I may employ.

Fig. 7 is a sectional view of a flexible wiper element which I employ; and,

Fig. 8 is a view similar to Fig. 2 showing only a part of the construction on an enlarged scale and showing a modification with parts removed.

In Fig. 1 of the drawing, I have diagrammatically illustrated one method of carrying my invention into effect and of treating strands of the class under consideration. In this figure, 10 represents a reel containing the strand 11 to be treated. In this connection it will be understood that the reference in the specification to "strand" will be interpreted to mean a wire, cotton, silk or other strand or an electric conductor disposed in casings, jackets or sheaths of various kinds and classes and including what are known as cable and electric conduits.

The strand 11 from the reel 10 first passes into and through a tank 12 containing the saturant, compound or other coating or finishing material by first passing over a sheave 13 at one end of the tank, downwardly around a sheave 14 in the tank and then out of the tank and over a sheave 15 from which the strand passes into and through one of my improved dual wipers or applicators 16. In some instances, the tank 12 will have suitable means of heating as indicated at 12a to maintain the desired temperature for the saturant or compound employed. After passing through the wiper 16 which performs functions and operations later described, the coated strand 40 passed downwardly into and through a cooling tank 17 or under a sheave 18 disposed therein. Cooling water 17a is introduced into the tank 17 through the pipe 19 and is discharged therefrom into a suitable drain 20.

At 21, I have indicated multiple compressed air nozzles or jets for removing any surplus of water that may prevail on the strand prior to its movement from the top of the tank. The strand 50 then passes into and through a trough 22 containing another compound or coating material, usually in the form of a thin film coating, the thickness or application of which is controlled by a wiper 23 of any conventional form, and in some 55

cases, a wiper such as indicated at 16 and later described may be employed at this point.

In the construction indicated, the compound is supplied to the trough 22 from a tank or container 5 24 by a pump 25 driven by a motor 26 and discharged into the trough through a jet or nozzle 27. At 28, I have indicated a caspan wheel operating in a water trough 29 over and around which the treated strand passes and finally is 10 wound on a receiving reel 30.

My improved dual wiper device 16 is indicated in detail in Figs. 2 to 5 inclusive and consists of two frame members or brackets 31 which may be secured to a suitable support such for example 15 upon the tank 12 as indicated in Fig. 1 of the drawing. The standards in these brackets are provided with elongated apertures 32 through which outwardly projecting studs 33 on the frame or stock 34 of the device pass to provide vertical 20 adjustment of the frame 34 in said brackets as well as angular or tilting adjustment thereof, the same being clamped in different positions of adjustment by nuts 33a in threaded engagement 25 with said studs as indicated in Fig. 3 of the drawing.

The frame 34 consists of a relatively large front plate 34a forming a splash apron having a relatively thick transverse rib 34b in which is detachably supported a striping or wiper die 35, 30 the latter being held in position by a set screw 35a. The frame 34 also includes a thicker back plate 34c joining the front plate by side arms 34d which extend from the ends of the rib 34b, thus forming between the back plate 34c and the rib 34b and front plate 34a a relatively large opening 36 through which the material removed from the strand by a flexible wiper element 37 supported in the back plate 34c may pass and drop back into the tank 12. In this connection, it 40 will be understood that the relative size of the complete frame 34 as well as the opening 36 formed therein will be proportionate to the size of the strand in connection with which the wiper is employed and will also depend upon the characteristics of and amount of the coating material 45 desired to be removed from the strand.

Pivotedly supported on a screw or pin 38 on the outer surface of the part 34c of the frame is a plate 39 having an outwardly extending angle member 39a, note Fig. 5, the lower end of the plate having a hook 39b engaging another screw or pin 38a to retain said plate in proper position and against outward displacement with respect to the part 34c. A pin 39c is also employed adjacent the pivot at 38 to engage the plate 39 to act as a stop or alignment pin to maintain the opening or threaded bore 39d of the plate 39 in proper alignment with respect to the center of the parts 34c of the frame or the centers of the die 55 35, and the wiper element 37, or the ports or passages 35b and 37a respectively thereof.

Adjustably mounted in the bore 39d is a compression screw 40, the outer enlarged end of which has a plurality of radial arms 40a by means 60 of which said screw may be rotated by hand to move a compression ring 41 toward and from the flexible wiper element 37. Mounted in the threads of the screw 40 at the free end thereof is a spring ring 40b, note Figs. 2 and 4 of the drawing, which 65 enters a recess in the inner end of the plate 39 and limits the outward movement of the screw, thus preventing accidental displacement of the screw 40 with respect to the plate 39 and at the same time, permits the free swinging of the plate 70 75 39 including the screw 40 into the position inquired

cated in dotted lines in Fig. 4 of the drawing in the insertion and removal of the ring 41 and element 37.

The ring 41 in the construction shown in Fig. 2 of the drawing has a relatively large opening 41a through which the conductor passes, and it is also preferable that the bore 40c of the screw 40 be large so as to provide free passage of the conductor therethrough, whereas the bore or passage 42 in the part 34c of the frame is preferably 1 larger than the bore 41a. The ring 40 has an enlarged collar 41b which rests upon the element 37 and aids in forcing the central portion of said element outwardly into the bore 42 in the manner indicated in Fig. 2 in the operation of reducing 15 the size of the bore or passage 37a in said element.

At this time, it will be understood that as the ring 41 is forced upon the element 37 by the screw 40, the material of the element 37 which is preferably composed of rubber is forced into the bore 20 or opening 42 and compressed symmetrically therein so as to maintain the proper axis to said bore, and at the same time, maintain a circular opening. In the compression and flexure of the element 37, it will also appear that the end of 25 the passage 37a directed to the left or toward the bore 42 is flared.

It will also be apparent that the greater the compression of the element 37, the greater will be the reduction in diameter of the passage 37a, 30 and the thickness of the element 37 may be varied to provide a wider range of compression, and these adjustments of the size of the passage 37a will 35 adopt a single element 37 to different sizes of strands. It will also be understood that in commercial practice, there is a wide range of wire sizes and conductor sizes employed, going into large cable sizes. The entire device is constructed in a number of sizes consistent with the drastic changes in diameters, whereas a single device 40 will compensate for numerous sizes wired within predetermined limits.

The ring 41 also includes laterally extending arms 41c, note Fig. 4, which extend into recesses 43 in the frame part 34c to key the ring against 45 rotation in the frame and permit only longitudinal movement with respect to the axis of the wire in the operation of the screw 40. This also avoids any possible rotation of the element 37, as will be apparent.

In Fig. 6 of the drawing, I have indicated at 44 a modified form of die which may be substituted for the die 35, and with this die, the bore 44a thereof is provided with a plurality of inwardly projecting ribs or fingers 44b adapted to engage 55 the strand or conductor to centralize the same in said die and to form by the recesses 44c between the projecting fingers 44b substantially even deposits of the compound on the strand, which deposits will be slushed into a circumferential coating of even thickness in passing through the wiper element 37, the surplus of the compound being removed as with the structure shown in Fig. 2 of the drawing. With the structure shown in this figure, the die first removes part of the surplus 65 compound on the strand, and after passing through the element 37, the compound on the strand is brought to a finished and desired size with the additional surplus removed.

In Fig. 8 of the drawing, I have shown a slight 70 modification of the construction shown in Fig. 2, wherein 45 indicates part of the frame similar to a part 34c, and 46 a ring similar to the ring 41. With this construction, the bore of the frame part 45 is made large and threaded to receive a plug 75

or die element 47 having a bore 47a therein which takes the place of the bore 42 in the structure shown in Fig. 2. The purpose of this construction is to provide a removable die element such as 47, wherein the size of the bore 47a thereof may be increased or decreased so as to care for materially different sized wires in one device.

The change in the die element 47 is, of course, consistent with the change incorporated in the die 35. In like manner, a supplemental ring 48 is employed in the ring 46 being in threaded engagement therewith so that the bore 48a of the supplemental ring may be increased or decreased consistent with the change in the bore 47a of the die element 47, and at the same time, to modify the diameter of the projecting collar portion which is formed by the flange 48b of the supplemental ring 48. The ring 46 also includes the laterally extending arms 46a to key the same against rotation with respect to the frame member 45, the latter being part of a frame structure similar in all other respects to the structure shown in Fig. 2 of the drawing.

It will be understood that the wiper unit or the frame 34 thereof will be adjusted with respect to its support so as to position the several passages of the frame in alinement with the strand suspended between the two points of support, namely, the sheaves 15 and 18, or any other supports or guides which may be provided. By maintaining the strand centrally with respect to the passages in the wiper unit, and especially the element 31 thereof, the application of an even thickness coating on the strand is made possible. It will also be understood that different types of coating materials may be employed on the strand, depending upon the results desired or required, and as previously stated, the strand may be treated with two or more coating materials, each of which may be applied by the use of the dual unit wiper disclosed.

It will be understood that while I have shown certain details of construction for carrying my invention into effect, I am not necessarily limited to these details nor am I limited to the specific use of the device herein illustrated, and various other changes in and modifications of the construction of the device and the method of its use herein shown and described, may be made within the scope of the appended claims without departing from the spirit of my invention or sacrificing its advantages.

Having fully described my invention, what I claim as new and desire to secure by Letters Patent, is:

1. A dual wiper device of the class described including spaced wiper elements having passages therein through which a strand to be wiped is adapted to pass, one of said elements being composed of yielding material, means cooperating with said element to compress the same to vary the size of the passage therein, the axis of the passages of said elements being in common alinement, said first named means including a member maintaining the contour of the passage in said yielding element in the operation of varying the size of such passage, and the passage of the other of said elements having inwardly projecting and circumferentially spaced fingers for providing even thickness deposits of a coating material on said strand.

2. In a dual wiper of the class described, a frame having spaced supporting members and tubular wiper elements detachably coupled with said members with the bores or passages of said ele-

ments disposed in common axial alinement with respect to each other, one of said elements being composed of rubber and compression means movably mounted in connection with the member supporting said last named element to act upon said element to vary the size of the passage therein, said last named means including a ring operating upon one side surface of said compressible element, and tubular parts detachable with respect to said ring and the supporting member of said compressible element for adapting the wiper to work pieces of varying sizes.

3. A wiper of the class described comprising a frame, a wiper element in said frame composed of yielding material and having a circular passage therein through which an elongated member of round cross sectional form is adapted to pass, compression means movably supported in the frame and cooperating with said element to adjust the size of the passage therein while maintaining the circular contour thereof, said means comprising an adjustable screw and a sliding but non-rotatable ring disposed between the screw and said element, and said frame and ring having registering passages, one of which is of greater diameter than the other whereby in the compression of said element, the passage therein will be flared outwardly to one side of said element.

4. A wiper device for electric conductors, said device comprising a frame, a support for said frame, tubular wiper elements arranged in common alinement and spaced in said frame and through which a conductor to be wiped is adapted to pass, manually actuated means adjustable in the frame for positively varying the size of the passage through one of said elements to regulate the application of a coating material to the conductor, and means for adjustably mounting the frame in connection with said support to align the wiper elements with the path of movement of a conductor passed therethrough.

5. A wiper device for apparatus of the class described comprising a frame, a support therefor, means for adjustably mounting the frame in connection with the support, said frame including spaced tubular wiper elements, one of said elements comprising a disk of yielding material seating in said frame with the passage of said disk arranged adjacent and opening into a materially larger opening in said frame, a ring mounted within the frame and engaging said disk, and a compression screw in threaded engagement with the frame and cooperating with said ring to move the same in the direction of said disk to compress said disk for varying the size of the passage therethrough.

6. A wiper device for apparatus of the class described comprising a frame, a support therefor, means for adjustably mounting the frame in connection with the support, said frame including spaced tubular wiper elements, one of said elements comprising a disk of yielding material seating in said frame with the passage of said disk arranged adjacent and opening into a materially larger opening in said frame, a ring mounted within the frame and engaging said disk, a compression screw in threaded engagement with the frame and cooperating with said ring to move the same in the direction of said disk to compress said disk for varying the size of the passage therethrough, and means for keying said ring against rotation in said frame.

7. A wiper device for apparatus of the class described comprising a frame, a support therefor, means for adjustably mounting the frame in

- connection with the support, said frame including spaced tubular wiper elements, one of said elements comprising a disk of yielding material seating in said frame with the passage of said disk arranged adjacent and opening into a materially larger opening in said frame, a ring mounted within the frame and engaging said disk, a compression screw in threaded engagement with the frame and cooperating with said ring to move the same in the direction of said disk to compress said disk for varying the size of the passage therethrough, means for keying said ring against rotation in said frame, and the side surface of the ring engaging said disk having an annular projection arranged adjacent the passage in said disk.
8. A dual wiper device of the class described including spaced wiper elements having passages therein through which a strand to be wiped is adapted to pass, one of said elements being composed of yielding material, a supporting frame for said element having an opening materially larger than and registering directly with the passage in said element, a compressing ring mounted in said supporting frame and engaging the other surface of said element, manually adjustable means engaging said ring to compress said element to control the size of the passage therein, the passages of both of said elements being in common alinement, and means for adjusting said supporting frame to properly position and aline the passages of said elements with respect to the path of travel of the strand passed therethrough.
9. A wiper device of the class described comprising a frame having spaced plates with a chamber therebetween, the plates having passages arranged in common alinement and the passage of one plate forming one wiper element, an apertured disk of yielding material abutting the other plate and the aperture of which registers directly with and is smaller than the opening of the other plate and forming the other wiper element, a compression ring engaging the other surface of said disk, and a member adjustable with respect to the second named plate and engaging said ring to vary the size of diameter of the aperture in said yieldable element.
10. A wiper device of the class described comprising a frame having spaced plates with a chamber therebetween, the plates having passages arranged in common alinement and the passage of one plate forming one wiper element, an apertured disk of yielding material abutting the other plate and the aperture of which registers directly with and is smaller than the opening of the other plate and forming the other wiper element, a compression ring engaging the other surface of said disk, a member adjustable with respect to the second named plate and engaging said ring to vary the size of diameter of the aperture in said yieldable element, and means for movably supporting said adjustable member in connection with said plate to permit attachment and detachment of said disk and ring.
11. A wiper device of the class described comprising a frame having spaced plates with a chamber therebetween, the plates having passages arranged in common alinement and the passage of one plate forming one wiper element, an apertured disk of yielding material abutting the other plate and the aperture of which registers directly with and is smaller than the opening of the other plate and forming the other wiper element, a compression ring engaging the other surface of said disk, a member adjustable with respect to the second named plate and engaging said ring to vary the size of diameter of the aperture in said yieldable element, means for movably supporting said adjustable member in connection with said plate to permit attachment and detachment of said disk and ring, and means for keying the ring against rotation with respect to said plate.
12. A wiper device of the class described comprising a frame having spaced plates with a chamber therebetween, the plates having passages arranged in common alinement and the passage of one plate forming one wiper element, an apertured disk of yielding material abutting the other plate and the aperture of which registers directly with and is smaller than the opening of the other plate and forming the other wiper element, a compression ring engaging the other surface of said disk, a member adjustable with respect to the second named plate and engaging said ring to vary the size of diameter of the aperture in said yieldable element, means for movably supporting said adjustable member in connection with said plate to permit attachment and detachment of said disk and ring, means for keying the ring against rotation with respect to said plate, a support for said frame, and means including rotatable and slidable bearings for mounting the frame in connection with said support to provide sliding and swinging adjustment of the frame with respect to the support.
13. A wiper for applying even and substantially concentric coatings of compounds on a strand passed therethrough comprising a frame, spaced tubular wiper elements on said frame with a large opening in the frame between said elements, one wiper element being adapted to remove the bulk of the surplus compound from the strand in its passage therethrough, the other wiper element being exposed directly to the large opening in said frame and being adapted to remove additional compound from the strand to reduce the same to a substantially given coating thickness in the passage of the strand through the second named element, and manually actuated means positively acting upon the second named element for adjusting and regulating the size of the passage therein to regulate the application of the compound to said strand.

ANTHONY P. HINSKY.
